UNITED STATES PATENT OFFICE

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed May 5, 1934. Serial No. 710,979.

My invention relates to an apparatus for starting an engine, more particularly an internal combustion engine, and pertains to the drive or transmission forming the driving connection between the prime mover, such as an electric motor and a member of the engine to be started such as the flywheel thereof. The object of my invention is to provide a simple, efficient and reliable drive characterized more particularly by the provision of two clutches arranged in the line of transmission of torque and cooperating with both ends of a yielding means, such as a compression spring. My drive in its preferred form, in which automatic disconnection of the transmitting elements is possible, is adapted to take care of any load condition beyond a predetermined maximum (such as results from the backfire of the engine or arrest of the longitudinal movement of the driving member or pinion from any cause) which is liable to be injurious or destructive to the starting apparatus or to the engine member with which it is operatively connected.

While my invention is not limited in this application and use to any particular construction of starting apparatus or any particular form of drive, I have incorporated the same in the well known Bendix drive and the same will, therefore, be described in connection therewith. Speaking in general terms, and referring to the preferred form, my new drive includes a rotatable member such as a screw shaft and a driving member or pinion mounted thereon for longitudinal movement thereof and rotary movement therewith and adapted to be automatically advanced into mesh with the engine member such as the flywheel. This screw shaft is driven by the extended armature shaft or a countershaft driven therefrom through a pair of yieldable clutches working upon the ends of a heavy coiled spring interposed between them with the result that in case of overload the members of each clutch will disengage and break the driving connection between the armature shaft and the screw shaft and permit such armature shaft to run freely or idly. In this manner when the predetermined maximum load is reached, the clutches

are automatically declutched or disabled and the driving connection between the starting motor and the screw shaft will thereupon be broken, and in the case of backfire the pinion may be rotated by the flywheel in reverse direction without any injury to the parts. In a modified form, the clutch members while also cooperating with both ends of the spring are not permitted to disengage but to yield, one member of a clutch with respect to the other, whereby there is provided an initial yielding drive and a positive final drive.

In the drawings, Figure 1 is a sectional elevation of my starting apparatus; Fig. 2 an end view of the drive; Fig. 3 a detail view of the pinion stop; Figs. 4 and 5 cross sections on the same section line of Fig. 2 but looking in opposite directions as indicated by the arrows corresponding to the particular figure; Fig. 6 a view similar to Fig. 1 but showing more of the parts in elevation and less in section; Figs. 7 to 12 elevations of the clutch members; Fig. 13 an end view of the screw shaft; Fig. 14 an elevation of the screw shaft; Fig. 15 an end view of the pinion; Fig. 16 a side elevation thereof; Fig. 17 an end view of an actuating sleeve; Fig. 18 a side elevation thereof; Fig. 19 an end elevation of the enclosing casing or barrel; Fig. 20 a side elevation thereof; Fig. 21 one of the keys employed, and Fig. 22 a detail of a modified form of construction.

Referring to the particular embodiment of my invention as herein shown, the drive is here directly driven inasmuch as the driving shaft 1 is the extended armature shaft of the electric motor indicated at A, but it will be understood that my invention is applicable to the indirect drive type in which the drive is mounted upon a countershaft with respect to said armature shaft. Moreover, the particular drive shown is of the in-board type inasmuch as the driving member or pinion 2 moves inwardly when going into mesh with the flywheel, but it will be understood that my invention is equally applicable to a drive of the outboard type.

Upon the driving shaft 1 there is mounted a rotatable member which in the present instance is in the form of a hollow screw shaft

3 on which the driving member or pinion is threaded. This pinion is thus mounted upon the screw shaft for rotary movement therewith and for longitudinal movement thereof 5 to mesh with the teeth 4 of the flywheel 5 of the engine to be started. This longitudinal movement of the pinion for the cranking operation is stopped by a stop nut 6 secured to the inner end of the screw shaft. In the 10 present instance, there is no direct contact between the pinion and the stop nut inasmuch as there is interposed between the pinion and the stop nut a collar 7 slidable longitudinally upon the smooth portion of the 15 screw shaft and against the tension of a light spring 8. By preference, the pinion is provided at its outer or non-engaging end with a projecting disc 9 which may or may not be integral therewith, but which is here shown 20 separate and secured thereto.

The driving connection between the driving shaft 1 and the driven member 10 of the screw shaft comprises more particularly the yieldable clutches which constitute the feature of my present invention and consists of the following mechanism. A sleeve 11 is secured to the driving shaft by means of the screw 12 and a key 13. This sleeve has the 25 particular shape illustrated in Figs. 17 and 18 wherein it is seen that the same has two opposite flattened faces 14 and also a reduced outer diameter in order to form a shoulder 15. It is upon this sleeve that the movable or longitudinally slidable members of both 30 35 clutches and the fixed or non-sliding member of one of these clutches are mounted.

There are two clutches both of which are located within the casing or barrel 16 and arranged in the line of transmission of torque 40 between the driving shaft 1 and the screw shaft. These clutches are positioned at opposite ends of this barrel and between them is interposed a heavy coiled compression spring 17. The outer clutch is composed 45 of two members 18 and 19 which are illustrated separately in Figs. 7, 8, 9 and 10. These members have corresponding or complementary inclined clutch jaws 20 and 21 respectively so that the transmission of 50 torque in excess of a predetermined amount will cause the clutch member 19, hereinafter for convenience called the movable member to slide longitudinally out of engagement with its corresponding member which is incapable of longitudinal movement and is, 55 therefore, hereinafter for convenience called the fixed member although, of course, it is capable of rotation. The fixed member 18 has a central circular bore fitting over the 60 sleeve 11 and, therefore, not connected therewith. On the other hand, the other clutch member 19 has a central bore which is of the same shape as the outer surface of the sleeve 11, that is it is provided with opposite flat 65 sides 22 as shown in Fig. 7 with the result

that this movable member is mounted upon the sleeve for rotation therewith and for longitudinal slidable movement thereon. The fixed clutch member 18 is secured at its periphery to the barrel 16 in suitable manner 70 as by means of the keys 23 interlocking with the slots 24 and 25 of the barrel and clutch member 18 respectively. A ring 26 is secured to the outer end of the barrel as by screw threading thereon and the same is provided 75 with an inwardly directed flange 27 fitting against the outer face of the clutch member 18 and against the shoulder 15 of the sleeve 11.

The inner clutch is substantially the same as the outer clutch with the exception that 80 the fixed clutch member 28 has an irregular shaped bore with flattened sides 29 whereby it is rotatably secured to the correspondingly flattened opposite sides 30 of the head 10 of the screw shaft. This fixed clutch member 85 28 is secured to the barrel 16 in the same manner as the clutch member 18, that is, by means of keys 23 interlocking with slots 31 and 32 of the barrel and clutch member 28 respectively. A ring 33 similar to the ring 90 27 is secured to the inner end of the barrel and has an inwardly directed flange 34 adapted to hold the clutch member 28 in place.

The other clutch member 35 is similar to 95 clutch member 19 inasmuch as it is of the same structure and operation, that is, it has inclined jaws 36 engaging corresponding jaws 37 of its cooperating clutch member and is rotatively connected with and mov- 100 105 able longitudinally upon the sleeve 11 against the tension of the spring 17. This spring is normally under a predetermined amount of tension which is exerted upon the movable clutch members 19 and 35 in order to keep them separated from each other and into engagement with their cooperating clutch members 18 and 28.

As above stated, the clutch member 28 is 110 rotatively secured to the head 10 of the screw shaft and in order to permit of the longitudinal movement of such shaft independently of this clutch member and against the tension of the coiled spring 38, and to also limit the outward movement of this screw 115 shaft, I provide a dowel pin 39 which extends through an opening 40, that is coincident with the slot 32 of the clutch member 28 as shown in Figs. 1 and 11. This pin projects inwardly and against the flattened 120 surface 41 of the screw shaft. A projection or small flange 42 at the extreme end of the screw shaft cooperates with the pin whereby the screw shaft is limited in its outward position as enforced by said spring 38. When the parts are assembled, the pin 39 is held in place by the key 23 as shown in Fig. 1.

In the present instance, I provide an abrupt stop for the outward travel of the pinion on the screw shaft which stop com- 125 130

prises a plate 43 set into a slot 44 in the head 10 of the screw shaft and held in place by a screw 45. As shown in detail in Fig. 3, this plate extends towards the screw thread 5 and over the outer end or extremity of the thread and in the path of movement of the shoulder 46 formed by cutting away one end of the pinion as shown in Fig. 16.

Describing the cycle of operation and beginning with the parts in their normal position as shown in Fig. 1, when the starting motor A is energized and its shaft 1 is rotated, the screw shaft will be rotated through the medium of the clutches and associated parts and the pinion will be caused to automatically advance into mesh with the teeth 4 of the flywheel. When this advance or inward movement of the pinion is stopped by the stop nut 6 and interposed collar 7, 15 the pinion will partake of the rotary movement of the screw shaft and the engine will be cranked. When the engine operates under its own power, the pinion will be automatically demeshed in the well known manner. 20

25 The torque of the motor is transmitted from the motor shaft 1 to the pinion and to the flywheel through the route and the parts as follows: The sleeve 11 being secured to shaft 1 is rotated by the motor and, in like manner, the two movable clutch members 19 and 35 being rotatively secured to this sleeve are rotated. The coiled spring being under compression and forcing the movable clutch members into engagement with their 30 cooperating clutch members, the torque will be transmitted from these movable members to such cooperating members and through the barrel and through the clutch member 28 to the screw shaft. Inasmuch as the clutch members 18 and 28 are both connected with the barrel 16 and are operatively connected with the movable clutch members 19 and 35 which are in turn rotatively connected with the sleeve 11, it follows that such assembly 35 rotates as a unit.

In case of an overload, as for instance, a flywheel that is stuck or offers an unusual amount of resistance or in case of a backfire or a back rock with the pinion in mesh with the flywheel, the jaws of the clutch members are so made as to automatically disengage by the inward movement towards each other of the movable clutch members 19 and 35 against the pressure of the heavy spring 17. 40 When this movement has been such as to cause a clearance between the clutch jaws, the sleeve and the two movable clutch members will rotate idly, and practically no torque will be transmitted in view of the fact that the driving connection at the 45 clutches has been broken or disabled. When the overload decreases to the predetermined amount, the clutches will become re-engaged and the torque will be transmitted in the normal manner.

It will be understood that the heavy spring 17 acts as a yielding driving connection in the normal cranking operation in view of the fact that it may be made of sufficient tension to yield somewhat against a tendency of the movable clutch members to move inwardly towards each other, but without becoming entirely disengaged from their cooperating clutch members. 70

In the event that the pinion teeth and the flywheel teeth should not properly register but should abut end to end, the screw shaft is adapted to move longitudinally towards the left in Fig. 1 against the tension of the spring 38, whereupon the pinion will be moved slightly rotarily in the well known manner and registry between the teeth thereby obtained and full mesh accomplished. 75

According to the modification shown in Fig. 22, a ring 47 is interposed between the two clutch members 19 and 35. This ring is of such width as to permit longitudinal movement of these clutch members but not separation or disconnection from their companion clutch members 18 and 28. As a result there is provided a yielding initial drive or transmission of torque and a positive final drive. In this form as in the preferred form, both ends of the spring 17 are utilized. 80

I claim:

1. An engine starter drive including a rotatable shaft, a driving member adapted to engage and drive a member of the engine to be started, a pair of clutches disposed in axial alignment, a spring interposed between them, a barrel enclosing the clutches and the spring, one member of each clutch being rotatively connected with the shaft and movable longitudinally with respect thereto, the other member of each clutch being rotatively connected with the barrel, and one of the latter members being operatively connected with the driving member. 90

2. An engine starter drive including a rotatable shaft, a driving member adapted to engage and drive a member of the engine to be started, a sleeve rotatively secured to the shaft, a pair of clutches in the form of rings encircling the sleeve, one member of each pair of clutches being rotatively secured to the sleeve and movable longitudinally thereon, a barrel enclosing the clutches and rotatively connected with the other members of the clutches, one of the latter being operatively connected with the driving member, and a yielding means for tending to hold the two movable clutch members into engagement with their cooperating members. 100

3. An engine starter drive including a rotatable shaft, a driving member adapted to engage and drive a member of the engine to be started, a sleeve rotatively secured to the shaft, a pair of clutches in the form of rings encircling the sleeve, one member of each pair of clutches being rotatively secured to 115

the sleeve and movable longitudinally thereon, a barrel enclosing the clutches and rotatively connected with the other members of the clutches, one of the latter being operatively connected with the driving member, and a coiled spring interposed between the two movable clutch members and tending to hold them into engagement with their cooperating members.

4. An engine starter drive including a rotatable shaft, a driving member adapted to engage and drive a member of the engine to be started, a sleeve rotatively secured to the shaft, a pair of clutches in the form of rings encircling the sleeve, one member of each pair of clutches being rotatively secured to the sleeve and movable longitudinally thereon, a barrel enclosing the clutches and rotatively connected with the other members of the clutches, one of the latter being operatively connected with the driving member, and a yielding means for tending to hold the two movable clutch members into engagement with their cooperating members, said barrel having means for retaining the last-named clutch members in place.

5. An engine starter drive including a rotatable shaft, a hollow shaft mounted thereon, a driving member mounted on the hollow shaft for rotary movement therewith and longitudinal movement thereof into engagement with a member of the engine to be started, a pair of clutches operatively connecting between the two shafts, one member of each clutch being rotatively connected with the rotatable shaft and movable longitudinally thereon, a yielding means between said latter clutch members tending to resist their longitudinal movements, a barrel enclosing the clutches and rotatively connected with the other members of the clutches, one of such latter clutch members being rotatively connected with the hollow shaft.

6. An engine starter drive including a rotatable shaft, a hollow shaft mounted thereon, a driving member mounted on the hollow shaft for rotary movement therewith and longitudinal movement thereof into engagement with a member of the engine to be started, a pair of clutches operatively connecting between the two shafts, one member of each clutch being rotatively connected with the rotatable shaft and movable longitudinally thereon, a yielding means between said latter clutch members tending to resist their longitudinal movements, a barrel enclosing the clutches and rotatively connected with the other members of the clutches, said hollow shaft having a longitudinal yielding movement on the rotatable shaft, and being rotatively connected with one of the last mentioned clutch members.

7. An engine starter drive including a rotatable shaft, a hollow shaft mounted thereon, a driving member mounted on the hollow

shaft for rotary movement therewith and longitudinal movement thereof into engagement with a member of the engine to be started, a pair of clutches operatively connecting between the two shafts, one member of each clutch being rotatively connected with the rotatable shaft and movable longitudinally thereon, a yielding means between said latter clutch members tending to resist their longitudinal movements, a barrel enclosing the clutches and rotatively connected with the other members of the clutches, said hollow shaft having a longitudinal yielding movement on the rotatable shaft, and being rotatively connected with one of the last mentioned clutch members, and means for limiting the longitudinal movements of the hollow shaft.

8. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connected with the sleeve and hollow shaft, and a coiled spring encircling the sleeve and interposed between the clutches with its opposite ends bearing thereagainst to hold the clutch members in clutching engagement.

9. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connected with the sleeve and hollow shaft, a coiled spring encircling the sleeve and interposed between the clutches with its opposite ends bearing thereagainst to hold the clutch members in clutching engagement, and a barrel encasing the clutches and operatively connected with one member of each of the clutches.

10. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connected with the sleeve and hollow shaft, one member of each clutch being rotatively connected with the sleeve and relatively movable longitudinally thereof, and a coiled spring interposed between said two movable clutch members to hold them normally into engagement with their cooperating clutch members.

11. An engine starter drive including a driving shaft, a sleeve rotatively connected therewith, a hollow shaft mounted on the driving shaft, a driving member mounted on the hollow shaft and adapted to engage a

- member of the engine to be started, a pair of clutches concentric of the sleeve and operatively connecting between the sleeve and hollow shaft, yielding means arranged between the clutches to normally hold the clutch members in clutching engagement, said hollow shaft being mounted for relative longitudinal movement on the driving shaft, and a spring interposed between the sleeve and hollow shaft and resisting such longitudinal movement of the latter. 10
12. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connecting between the sleeve and hollow shaft, yielding means arranged between the clutches to normally hold the clutch members in clutching engagement, said hollow shaft being mounted for relative longitudinal movement on the driving shaft, a spring interposed between the sleeve and hollow shaft and resisting such longitudinal movement of the latter in one direction, and means for limiting the movement thereof in the other direction. 20
13. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connecting between the sleeve and hollow shaft, yielding means arranged between the clutches to normally hold the clutch members in clutching engagement, said hollow shaft being mounted for relative longitudinal movement on the driving shaft, said sleeve having a counterbore at one end, and a spring interposed between the sleeve and hollow shaft and received by such counterbore. 30
14. An engine starter drive including a driving shaft, a sleeve rotatively connected therewith, a hollow shaft mounted on the driving shaft, a driving member mounted on the hollow shaft and adapted to engage a member of the engine to be started, a pair of clutches concentric of the sleeve and operatively connecting between the sleeve and hollow shaft, yielding means arranged between the clutches to normally hold the clutch members in clutching engagement, said hollow shaft being mounted for relative longitudinal movement on the driving shaft, a spring interposed between the sleeve and hollow shaft and resisting such longitudinal movement of the latter in one direction, and means for limiting the movement thereof in the other direction comprising a pin in the clutch connected with the sleeve, and a projection 40
- on the hollow shaft with which such pin operates. 50
15. An engine starter drive including a rotatable driving shaft, a driven shaft, a driving member mounted on the driven shaft for rotary movement therewith and longitudinal movement thereof, two clutches, the corresponding members of such clutches being operatively connected with said two shafts respectively, two corresponding members 75 which are connected with the driving shaft being mounted for longitudinal movement with respect thereto and with respect to their companion clutch members and single yielding means for holding such movable clutch 80 members extended and into engagement with their companion clutch members. 85
16. An engine starter drive including a threaded pinion, adapted for longitudinal advancement to engage and rotation to crank a member of an engine to be started, a threaded actuating member coacting with said pinion for advancing and rotating it, a driven shaft, and operative connections between said shaft and said actuating member for transmitting limited torque from said shaft to said actuating member and permitting longitudinal yield of said actuating member, said connections including in the line of torque transmission a clutch having members separable under applied torque and a spring opposing separation of said members and including a separate spring normally positioning said actuating member longitudinally 90 with respect to said shaft and yieldable to accommodate interference with the advancement of said driving member by abutment against said engine member. 100
